A. SWAROCZKI

TURBINE

Filed May 26, 1924

INVENTOR
Antoni Swaroczki
BY *John A. Polachek*
ATTORNEY

UNITED STATES PATENT OFFICE.

ANTONI SWAROCZKI, OF DETROIT, MICHIGAN.

TURBINE.

Application filed May 26, 1924. Serial No. 715,792.

To all whom it may concern:

Be it known that I, ANTONI SWAROCZKI, citizen of the United States, residing at Detroit, in the county of Wayne and State 5 of Michigan, have invented certain new and useful Improvements in Turbines, of which the following is a specification.

This invention relates to water, gas or steam turbines, the invention having for an 10 object the provision of a novel type of turbine provided with means for varying the effective area of the blade or vanes, thereof.

For further comprehension of the invention, and of the objects and advantages 15 thereof, reference will be had to the following description and accompanying drawing, and to the appended claims in which the various novel features of the invention are more particularly set forth.

20 Fig. 1 of the drawing is a face view, with parts broken away, of my improved turbine; showing it coupled up with an air compressor or the like to drive the latter.

Fig. 2 is a plan view.

25 Fig. 3 is a transverse vertical sectional view thereof, taken approximately along the line 3—3 of Fig. 1.

Referring now to the drawing, my improved turbine comprises a short cylindrical casing 10 which is mounted on an integral base 11, and which is here shown as provided at opposite ends with the radial flanges 10' to which the face plates 12 are secured as by the bolts 13. These face plates 30 are formed with bearing hubs 14 which support a shaft 15 on which the rotor of the turbine is mounted. This rotor comprises a member split, transversely of the axis thereof, into two halves 18.

40 This rotor is formed with a series of pockets 20 spaced evenly around the periphery thereof and whose forward walls 21 may be said to constitute vanes or blades against which the motive fluid impinges to drive 45 the rotor. Intake and outlet connections 22 and 23 respectively are provided on the casing 10.

To adjust or vary the effective area of the members 21 I may provide a series of adjustable plates or leaves 25 which are hinged at their forward sides to the rotor, being here shown as hinged on pins 26 fixed at opposite ends in the side walls of the pockets 20, the hinge axes of these leaves being parallel to the rotor axis. The free ends of these leaves are in close contact with the

front wall members 21 which latter are curved concentric to the hinge axes of the leaves.

The leaves are adapted to be adjusted outward, to vary the effective area of the members 21 by means of cams 28 formed on the periphery of a disk 29 and bearing against the inner faces of these leaves. This disk 29 is located between the two members 18 of the rotor to be capable of rotary adjustment with respect to the latter, the two members being spaced apart sufficiently to accommodate the disk between them, and may be secured together by bolts such as 31 passing through meeting bosses 32 on the respective members which project through arcuate openings 33 in the disk.

The disk 29 has connected thereto an elongated hub or sleeve 35 which freely encircles the shaft 15 and which projects through one of the face plates 12 and is locked to the shaft by a set screw 36 or any other suitable means. By loosening this screw, and giving the sleeve a slight rotary movement on the shaft, 75 the cams 28 may be made to move the leaves 25 outward to diminish the depth of the pockets and thereby lessen the area of the members on which the motive fluid impinges. The sleeve 35 is shown as provided 80 with a projecting pin 38 to be engaged by a suitable spanner when the sleeve is to be adjusted. Springs such as 40 may bear on the leaves 25 to urge the latter inward when adjustment is made to increase the effective 85 area of the members 21.

I have here shown my improved turbine arranged by means of a novel duplicate drive connection to drive an air compressor, pumps or the like. As here shown a pair of 90 crank wheels 45 are mounted on opposite ends of the shaft 15, and are connected by means of the connecting rods 46 with the opposite ends of a crosshead bar 47 slidable in fixed guide elements 48 and having connected thereto midway between its ends the end of the piston rod 49 of the cylinder 50 of the device being driven.

While I have illustrated and described a preferred embodiment of my invention it is 105 to be understood that I do not limit myself to the precise construction herein shown, and that various changes and modifications might be made therein without departing from the spirit and scope of the invention as 110 defined in the appended claims.

Having thus described my invention what

I claim as new and desire to protect by Letters Patent of the United States is as follows:—

1. A turbine comprising a casing, a rotor 5 therein, a shaft on which said rotor is fixed, a series of pockets formed in the periphery of said rotor, leaves hinged in said pockets for varying the effective depth thereof, a disk mounted on said shaft for rotary adjustment, and cam elements on said disk for bearing on the inner faces of said leaves and adapted to adjust the latter outward to decrease the depth of said pockets.
- 10 2. A turbine comprising a casing, a rotor therein, a shaft on which said rotor is fixed,

a series of pockets formed in the periphery of said rotor, leaves hinged in said pockets for varying the effective depth thereof, a disk mounted on said shaft for rotary adjustment, and cam elements on said disk for bearing on the inner faces of said leaves and adapted to adjust the latter outward to decrease the depth of said pockets, said disk having a sleeve extension surrounding said shaft and projecting from the casing and 20 adapted to be fixed to the shaft to secure the disk in adjusted position thereon.

In testimony whereof I have affixed my signature.

ANTONI SWAROCZKI.
